(57) **CLAIM**

The ornamental design for a two-piece cleat assembly, as shown and described.

DESCRIPTION

FIG. 1 is an exploded bottom perspective view of a two-piece cleat assembly showing my new design;

FIG. 2 is an assembled view thereof;

FIG. 3 is a bottom plan view of the cleat portion of the two-piece cleat assembly shown in FIG. 1;

FIG. 4 is an exploded top perspective view of the two-piece cleat assembly shown in FIG. 1;

FIG. 5 is a cross-sectional view taken along line 5—5 of FIG. 3;

FIG. 6 is a cross-sectional view taken along line 6—6 of FIG. 3;

FIG. 7 is a bottom plan view of the threaded tee portion of the two-piece cleat assembly shown in FIG. 1; and,

FIG. 8 is a side view thereof.

The broken line showing of a fragmentary portion of an athletic shoe with threaded socket in FIG. 1 is for illustrative purposes only and forms no part of the claimed design.
